UNITED STATES PATENT OFFICE.

ROGER W. GRISWOLD, OF ERIE, PENNSYLVANIA, ASSIGNOR TO THE GRISWOLD MANUFACTURING COMPANY, OF ERIE, PENNSYLVANIA, A CORPORATION OF PENNSYLVANIA.

STOVE DAMPER.

Application filed January 28, 1926 Serial No. 84,314.

Stove dampers are ordinarily provided with damper rods which may be forced through the stove pipe and extended through damper receiving openings in the damper and locked.

Such damper rods are ordinarily pointed and the stove pipe is usually perforated either with the damper rod itself, or some implement. These damper rods have been provided with shoulders for locking the damper rod with the damper plate and the wall of the stovepipe adjacent to the opening is enlarged ordinarily by the manipulation of the rod itself in forcing it through the opening. With the present invention, the damper plate is formed so that the rod may be inserted into the rod opening from either end and at the same time the shoulders are arranged nearer the point end than the handle end. This gives a greater length of handle for working the shoulder through the perforation in the stove pipe.

The invention is illustrated in the accompanying drawings as follows:

Fig. 1 shows a plan view of the damper. Fig. 2 a detached view of the rod. Fig. 3 a section on the line 3—3 in Fig. 1. Fig. 4 a section on the line 4—4 in Fig. 1. 1 marks the damper plate, 2 a minimum opening usually provided in the damper, and 3 a rod opening extending diametrically across the damper and ordinarily formed by an alternate arrangement of loops extending each side of the plate. In the present construction loops 4 are arranged at the edges of the damper plate, the loops 5 inwardly from the loops 4 and the loops 6 nearer the center than a loop 5, the loops 5 being arranged in each instance at the opposite side from the adjacent loops 4 and 6. The opening at the loop 4 is slightly tapered so as to more readily receive the rod and the opening as it passes through each of the loops is provided with a groove or enlargement 7 through which locking shoulders 8 of a rod 9 may pass.

The rod is provided with the usual point 10 and handle 11. The shoulders 8 are adjacent to the pointed end. Thus there is a

greater length of rod between the shoulders 8 and the handle 11. After the rod is inserted in a perforation in the stove pipe the shoulders 11 must be worked through this perforation. This is usually accomplished by a manipulation of the rod and this greater length of rod gives a greater leverage in rocking the rod back and forth in working the shoulders through the perforation. A cup 12 is placed around the rod at the handle end and a spring 13 is arranged on the rod and positioned in the cup, the spring operating against the handle to force the rod endwise toward the handle.

Open spaces 14 are formed in the plate adjacent to the broad opening 3 of sufficient size to permit the turning of the rod in the opening 3 when the shoulders 8 are brought into the spaces 14. Leading toward the center of the plate from the spaces are wedge shaped locking surfaces 15 so that when the rod is passed through the opening 3 to a position bringing the shoulders 8 into a space 14 at one end of the damper plate the rod may be turned bringing the shoulders 8 across the wedge surfaces 15. The return movement of the rod under the influence of the spring 13 moves the shoulders 8 along the locking surfaces 15 and thus locks the rod against turning in the plate and locks the rod in place in the plate.

What I claim as new is:

In a stove damper, the combination of a damper rod having a point, a handle and a laterally projecting shoulder more nearly adjacent to the point than to the handle; and a damper plate having a rod opening shaped to receive the rod from either end of the opening and having a locking surface with an adjacent open space at each end of the rod opening, the open space permitting the turning of the inserted rod in the opening to bring the shoulder into position to engage with the locking surface upon a reciprocal movement of the rod.

In testimony whereof I have hereunto set my hand.

ROGER W. GRISWOLD
